ABSTRACT OF THE DISCLOSURE

A device for setting up building sites in respect of corner datum points thereof, comprises two pivotally connected rigid arms engageable at their free ends with fixing members driven into the ground. When the pivot point is disposed at the desired corner point, and the arms are spread apart and are engaged with the fixing members in the ground, the arms may be removed from the fixing members and the fixing members left in the ground. The corner datum point can then be re-established by the pivot point simply by applying the arms again to the fixing members.

The invention relates to devices for use in the marking out of building sites.

When marking out building sites it is customary to use optical sighting procedures to ensure that corners of a marked out region are square. Recently it has been proposed to use for the optical sighting a device having two sighting paths which are accurately disposed at right angles to each other. These sighting paths may be provided by two telescopes having their axes at right angles. Such a sighting device is mounted on an adjustable cantilever support from a tripod and has a vertical axis which intersects the axes of the telescopes, the vertical axis being coincident with the axis of a downwardly extending tube in which a rod is slidably guided. The rod can be fixed in any position relative to the tube by means of a thumbscrew, and has a pointed or cup shaped lower end.

The lower end of the slide rod provides the actual datum point after the device has been properly set up, and this datum point can be marked by means of a marker peg placed in the ground in alignment with the said lower end. However, the position of the marker peg is lost during subsequent trenching operations for foundations. It is therefore customary to project outwardly from the conceptual position of the marker peg by a predetermined amount, for example two feet, and to mark these projected positions, so that after trenching, inward projection allows the original conceptual marker position to be re-established. This projection is a cumbersome procedure and increases the cost in setting up a building site.

The present invention consists in a device for use in the setting up of building sites by transferring co-ordinates of a corner datum point of two arbitrary points spaced apart from said corner datum point and enabling said corner datum point to be re-established when desired, the device comprising two rigid arms pivotally connected together at one end and having rigid means mounted on their other ends for engagement with fixing members adapted to be driven into the ground. Each of the rigid arms and its associated rigid engageable means constitutes an assembly which is rigid throughout from the pivot point to the engageable means. The arrangement is such that when the pivot point of the two arms is in register with the corner datum point and the engagement means at the other ends of the arms are engaged with fixing

2

members and the fixing members driven into the ground, the device can be removed from the fixing members, the corner datum point being re-established by the said pivot point when the device is again engaged with the fixing members.

5 In order to make the invention clearly understood, reference will now be made to the accompanying drawings which are given by way of example and in which:

FIG. 1 is a perspective view of a setting up device according to the invention

10 FIG. 2 is a perspective view of a fixing device shown engaged by an end of an arm of the device of FIG. 1;

FIG. 3 is an elevation view of the fixing device of FIG. 2, to a larger scale than FIG. 2; and

15 FIG. 4 is a plan view of the setting up device, shown in its position of use.

The setting up device has two arms 1 and 2 pivotally connected at one end by a rivet or bolt 3 which has a spike 4 which can readily be brought into a position of register with the vertical axis of the known optical sighting device mentioned above. At the other end, each arm 1 and 2 has a hole 5 flanked by a stop 6 and a lug 7 carrying a thumbscrew 8.

20 Fixing members 9 are provided which are adapted to be driven into the ground. The fixing members 9 have shanks 10 over which the arms 1 and 2 can engage by means of the holes 5. The shank 10 of each fixing member 9 is mounted by a plate 11 which carries spikes 12 for securing the fixing member in the ground. The thumbscrews 8 enable the arms 1 and 2 to be firmly secured to the shanks 10.

25 When a corner datum point for a building site has been obtained by use of an optical sighting device or by any other known means, the spike 4 of the device of the invention is brought into register with the corner datum point, the arms 1 and 2 being spread apart so as to provide a reasonably wide base between the holes 5, although it is not necessary for the arms 1 and 2 to be at a right angle to each other. The fixing members 9 are driven into the ground at points defined by the holes 5 and with the two arms of the device held by the two fixing members 9 the spike 4 is thus held fixed. After the fixing members 9 have been driven into the ground, the device can be removed from the fixing members, leaving the fixing members remaining in the ground. When it is again desired to re-establish the corner datum point, it is simply necessary to re-apply the device to the fixing members, whereupon the spike 4 will again be disposed in alignment with the corner datum point.

30 35 40 45 50 Since the fixing members 9 are disposed at some distance, for example two feet, from the corner datum point, trenching of the site can readily be effected after the device is removed from the fixing members 9. If desired, the fixing members 9 can be driven into the ground to such an extent that they are below ground level, whereby a trenching machine can run over them without dislodging them.

I claim:

55 60 65 70 75 80 85 90 95 1. A device for use in the setting up of building sites by transferring co-ordinates of a corner datum point of two arbitrary points spaced apart from said corner datum point and enabling said corner datum point to be re-established when desired, said device comprising two fixing members adapted to be driven into the ground; two rigid arms pivotally connected together at one end at a pivot point; and rigid engageable means mounted directly on the other end of each arm respectively and being detachably engageable with said fixing members, each of said rigid arms and its associated rigid engageable means mounted thereon constituting an assembly which is rigid throughout from said pivot point to said

engageable means, whereby when said fixing members are driven into the ground and said pivot point is in register with the corner datum point and said engageable means are engaged respectively with said fixing member, said arms, said pivot point and said engageable means can be removed together from the fixing members, leaving the fixing members in the ground, and the corner datum point may be re-established by the said pivot point when said engageable means are respectively re-engaged with the fixing members.

2. A device as defined in claim 1 wherein each of said fixing members comprises a shank, and wherein each arm at its said other end comprises means defining an aperture for engaging over the shank of the respective fixing member, each said other end having stop means flanking said aperture for engaging against the associated shank and means flanking said aperture and carrying a thumbscrew disposed opposite said stop means, said thumbscrew serving for engaging the shank and thus establishing a firm connection between said arm and the respective fixing member.

3. A device as defined in claim 2, wherein each of said fixing members comprises a plate through which the said shank extends, and a plurality of spikes extending from said plate for engaging in the ground.
